CLAIM

The ornamental design for a magnetic loop adapter, as shown and described.

DESCRIPTION

FIG. 1 is perspective view of a first embodiment of a magnetic loop adapter showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is another perspective view thereof, shown in a used condition with an oval and two rectangles shown in broken lines;

FIG. 9 is perspective view of a second embodiment of a magnetic loop adapter showing our new design;

FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a bottom view thereof; and,

FIG. 16 is another perspective view thereof, shown in a used condition with an oval and two rectangles shown in broken lines.

The broken lines in the figures are included for the purpose of illustrating portions of a magnetic loop adapter and form no part of the claimed design.
